UNITED STATES PATENT OFFICE.

HENRY EARLE, OF MONTREAL, QUEBEC, CANADA.

ORE-CONCENTRATOR.

1,085,596.

Specification of Letters Patent.

Patented Feb. 3, 1914.

Application filed May 3, 1913. Serial No. 765,336.

To all whom it may concern:

Be it known that I, HENRY EARLE, of Montreal, county of Hochelaga, in the Province of Quebec and Dominion of Canada, have invented certain new and useful Improvements in Ore-Concentrators, of which the following is a specification.

My invention relates to an ore concentrator of that class in which a conical pan with spiral riffles is used and it relates particularly to an improved construction of the ore concentrator shown and described in my United States Letters Patent No. 987,866 dated Mar. 28, 1911.

In my concentrator as described in my former patent, I made use of a vibratory shallow, generally conical pan, rotatable on an axis which was inclined to the perpendicular so that the lower portion of the conical pan would be substantially horizontal. A narrow upwardly extending rim surrounded the pan so that in operation the water formed a shallow pool at the lower or level portion of the pan. The ore was discharged into this pool and the vibration or reciprocation of the pan caused the ores to stratify, the heavy ore settling down between the riffles and the tailings being washed laterally across the riffles by means of the wash water.

The pan had an intermittent turning movement in addition to its shaking motion and this turning movement brought the tailings and concentrates partly out of the pool of water at each turn of the pan. This material was continually washed back into the pool by the action of the wash water which was applied on the sloping side of the pan above the pool and on the side up which the material was being moved.

It was supposed that the concentrates having become separated from the tailings in the pool the two materials would remain separated as they were washed back into the pool, that the heavy concentrates would follow the riffles and the tailings would be washed laterally across them and over the edge of the rim. It was found however, in practice, that each time the pan turned a part revolution the wash water as it washed the concentrates and tailings back into the pool would so agitate the water in the pool that the heavy ores which had settled behind the riffles would be stirred up and washed laterally over the riffles, thus escap-

ing over the edge of the pan. I have remedied this difficulty by means of my present invention which consists essentially of securing to the tops of the spiral riffles a series of transverse riffles. These transverse 60 riffles enable me to do away with the pool used in my former construction and to accomplish the result aimed at in a far more perfect manner as hereinafter more fully set forth.

I have illustrated my invention by means of the accompanying drawing, in which I show the rotating pan of my former machine provided with transverse riffles over the spiral riffles and without showing the 70 arrangements for mounting and turning which are the same as in my former patent.

In the drawing Figure 1 is a plan of the pan constructed according to my present invention and looking directly into it parallel 75 with its axis, and Fig. 2 is a vertical section through the pan with a portion of the frame and adjacent parts in position, reference being had to my former patent for other details of construction common to my present 80 invention.

Referring to the drawings, the pan generally is designated by A, the outer conical portion by a, the inner conical portion by a' and the discharge opening by a².

b b are the spiral riffles terminating at the edge of the pan and at the central opening, e is a portion of the frame to which is secured the wash water launder d.

As stated, I prefer in this form of machine to dispense with the upwardly turned rim and I now prefer to make use of a downwardly turned rim a³ which does not confine the water but allows it to run freely over the edge of the pan.

To effect the more complete separation of the heavy ores and the lighter material I provide a series of transverse riffles c which are secured to the tops of the spiral riffles and extend laterally across them. They are 100 preferably applied to the riffles of the outer conical section of the pan and they extend as here shown, from the edge of the pan to a point outside the line where the two conical sections join. They thus cover a portion 105 of the horizontal section of the pan which in my former construction was occupied by the pool. The transverse riffles are spaced close enough to one another to obtain the effect desired, which is as follows:—When 110

the bed of ore and water contained in the pan is given a shaking or oscillating motion, the cross riffles keep the bed of ore loose and open so that the heavier particles of ore quickly settle down through the lighter material and collect on the bottom of the pan between the spiral riffles, the heavier ore particles being thereby protected from the cross flow of water not only by the spiral 5 riffles but also by the covering or layer of light material on top. Another important effect of the cross riffles is to spread the ore and water in a thin bed or sheet by means of the slow turning motion of the pan. The 10 ore bed and water by this means are carried partly up the sloping side of the pan and more effectively separated by the wash water. The lighter particles of waste material being on top of the heavier ore particles are carried by the cross riffles farther up the slope of the pan so that there is a distinct division laterally between the tailings and the concentrates. The tailings occupying the upper part of the slope are carried 15 by the wash water to the edge of the pan and discharged, the concentrates being protected by the band of tailings from the action of the wash water. Another effect of the cross riffles is to increase the capacity 20 of the machine by causing the tailings to be more quickly removed. This is done by their action in directing the flow of wash water across the spiral riffles and thereby hastening the discharge of the tailings. The 25 heavier ore particles or concentrates lying below the cross riffles are not subjected to this action. The capacity of the cross riffles for quickly removing the tailings can be increased by placing them at a more acute 30 angle with the spiral riffles.

The cross riffles may be of any required cross section and secured to the tops of the spiral riffles in any desired manner. They may extend in a radial direction as here 35 shown, making right angles with the spiral riffles or they may cross the spiral riffles at more or less acute angles curving from the center of the pan toward the edge.

The cross riffles may be used in connection with a raised rim which forms a water pool or on any concentrator using a pan of any desired form with spiral riffles for gradually lifting the concentrates by the rotation of the pan.

I claim;—

1. An ore concentrator of the class described consisting of a generally conical rotary pan with an inclined axis and an internal discharge opening, a series of spiral riffles terminating at said discharge opening and a series of cross riffles extending transversely across said spiral riffles and superimposed thereon. 55

2. An ore concentrator of the class described consisting of a generally conical rotary pan with an inclined axis and an internal discharge opening, a series of spiral riffles terminating at said discharge opening, and a series of radially disposed cross riffles extending transversely across said 60 spiral riffles and superimposed thereon. 65

3. An ore concentrator of the class described, including the combination of a rotatable pan having its axis of rotation inclined to the perpendicular and having a 75 central opening, said pan having an outer conical section the lower portion of which is substantially horizontal, an inner conical section the lower portion of which inclines upward to said opening, a series of spiral riffles 80 the inner ends of which terminate at said opening and a series of riffles extending transversely across the spiral riffles on said outer conical section and being superimposed thereon. 85

4. An ore concentrator of the class described, including a generally conical rotatable pan adapted to rotate on an inclined axis to bring the lower portion of the pan substantially horizontal, said pan having 90 spiral riffles and an unobstructed rim and being provided with a series of transverse riffles superimposed on said spiral riffles. 95

5. An ore concentrator of the class described, including a generally conical rotatable pan adapted to rotate on an inclined axis to bring the lower portion of the pan substantially horizontal, said pan having spiral riffles and being provided with a series of transverse riffles superimposed on said 100 spiral riffles.

In testimony whereof I have affixed my signature, in presence of two witnesses.

HENRY EARLE.
